UNITED STATES PATENT OFFICE.

WALTER L. BODMAN, OF CINCINNATI, OHIO, ASSIGNOR TO ISAAC RHEINSTROM, OF CINCINNATI, OHIO.

BOTTLE-STOPPER.

No. 927,771.

Specification of Letters Patent.

Patented July 13, 1909.

Application filed October 26, 1908. Serial No. 459,530.

To all whom it may concern:

Be it known that I, WALTER L. BODMAN, subject of the King of Great Britain, residing at Cincinnati, in the county of Hamilton and 5 State of Ohio, have invented certain new and useful Improvements in Bottle-Stoppers, of which the following is a specification.

My invention relates to a hollow, ductile metallic cap for sealing bottles as a substitute 10 for the ordinary cork.

I am aware that various attempts have heretofore been made to utilize this principle, but such prior efforts, so far as I am aware, have failed to take into consideration the influence 15 on the cap of the resistance of the internal gas pressure to the driving force, and have also produced caps which were structurally unequal to the strain of the driving force and would hence collapse. Again, the physical 20 characteristics of such prior caps has been such that the bottle seal was neither perfect nor permanent. These disadvantages which are practically prohibitive have been entirely overcome by my invention, the features of which will be more fully 25 set forth in the description of the accompanying drawings, forming a part of this specification, in which:—

Figure 1 is a central vertical section 30 through the neck of the bottle and cap, illustrating the cap in position for insertion within the neck. Fig. 2 is a similar view with the cap inserted. Fig. 3 is a section of cap blank. Fig. 4 is a top plan view of cap.

1 is the neck of the bottle and 2 is the hollow, ductile, metallic cap. The central portion is substantially a flat disk 3, the edges of the disk have the upward bend 4, the outward bend 5, and the downward bend 6, and 35 in cross-section the cap tapers outwardly from the center, so that the downturned wall is relatively the most flexible portion. From this construction it appears that the disk portion of the cap is countersunk and constitutes 40 the structurally strongest portion of the cap, so that it will not collapse under the driving force. The tapering downturned peripheral wall is flexible, and its tapered portion closely engages the inner surface of

the bottle neck, and under the influence of 50 the drive, the gas compression caused by the entering cap, is a laterally expansive force operating upon the most sensitive portion of the cap. Thus the drive exerts an external compression laterally and the internal resistance 55 causes an expansive lateral action upon parallel horizontal section lines through the walls, the result of which is that the side walls of the cap following the lines of least resistance, tend to conform to the contour of 60 the neck of the bottle, thus forming an effective hermetic seal. This action is accentuated by the fact that the driving blow on the central, thicker disk portion of the cap, tends to make the thin edge of the wall fly 65 out and forcibly contact the glass surface of the neck. The effect of the gas compressed under a cap of this shape, wider at the top when in position, is mechanically that of a wedge, tending to forcibly retain it in its 70 driven position.

The cap may be easily extracted by a device fitting into the countersunk portion of the cap externally presented, but as this forms the subject of another invention, I will 75 not here describe it in detail.

Having described my invention, I claim:—

1. A bottle seal consisting of a hollow, ductile, metal cap, the material tapering outwardly in cross section, and having a 80 depending, peripheral wall, said cap diametrically approximating the orifice to be sealed, whereby under the opposing forces of the drive and the internal resistance of the gas the wall undergoes an external compression 85 at one point and lateral expansion at another, hermetically sealing the bottle, substantially as described.

2. A bottle seal consisting of a hollow, ductile cap, the material tapering outwardly 90 in cross-section and having a depending peripheral wall entering the neck of the bottle, said cap being diametrically approximate to the diameter of the orifice to be sealed, whereby under the opposing forces of the 95 drive and the internal resistance of the gas the wall undergoes an external compression at one point and lateral expansion at another,

hermetically sealing the bottle, substantially as described.

3. A bottle seal consisting of a hollow, ductile cap, the material tapering outwardly in cross-section and having a depending peripheral wall entering the neck of the bottle, the central disk portion of the cap being countersunk, presenting an external orifice for extracting, the said cap diametrically

approximating the orifice to be sealed, substantially as described. 10

In testimony whereof, I have hereunto set my hand.

WALTER L. BODMAN.
